ELECTRIC CIRCUIT BREAKER

Georges Balachowsky, Paris, France, assignor to
General Electric Company, a corporation of
New York

Application December 2, 1936, Serial No. 113,914
In France December 12, 1935

9 Claims. (Cl. 200—150)

This invention relates to electric circuit breakers of the liquid blast type wherein a blast or jet of arc-extinguishing liquid, such as oil for example, is projected through the arc by means actuated in accordance with opening of the circuit, and has for its principal object the provision of an improved circuit breaker of the aforesaid type which is simple and compact in construction, efficient and positive in operation and which requires a comparatively small amount of arc-extinguishing liquid.

My invention will be more fully set forth in the following description referring to the accompanying drawings, and the features of novelty which characterize my invention will be pointed out with particularity in the claims annexed to and forming a part of this specification.

Referring to the drawings, Fig. 1 is an elevational view partly in section of a high voltage electric circuit breaker embodying the present invention; Fig. 2 is a similar enlarged view showing a modified form of the contact construction; Fig. 3 is a similar view illustrating a construction generally similar to Fig. 1; Fig. 4 is an elevational sectional view of a modified form of circuit breaker embodying my invention; Figs. 5 and 6 are elevational views, partly in section, showing a modified form of circuit breaker in the closed and open circuit positions respectively; Fig. 7 is a partly diagrammatic view of a form of circuit breaker embodying the present invention; Fig. 8 is an elevational view partly in section of another form my invention may assume, and Figs. 9, 10, 11 and 12 illustrate a modified form of circuit breaker for interrupting high voltage circuits, Fig. 9 being an elevational sectional view, Fig. 10 being a plan view of the device shown by Fig. 9, and Figs. 11 and 12 being sectional views indicated respectively by the lines B—B and C—C of Fig. 10.

Referring to Fig. 1, there is shown one embodiment of my invention wherein the piston for producing the arc-extinguishing liquid blast is directly connected to the movable contact rod, and is operable within a cylinder concentric with respect to said rod. The contact rod which is of tubular construction in part is in communication with said cylinder so that the opening movement of the rod contact causes a blast of liquid through the tubular contact and through the arc at the point of contact separation.

As illustrated, the circuit interrupter, which is particularly adapted for interrupting high voltage power circuits, is in the closed circuit position. The circuit breaker comprises essentially a base or supporting structure 1 to which is se-

cured a mechanism housing 2 for the operating linkage generally indicated at 2'. The linkage is suitably actuated for moving the insulating rod 3, to which the movable rod contact 4 is secured, between open and closed circuit positions.

The insulating rod 3 is movable within and axially of a lower supporting insulator 5 which may be composed of a suitable ceramic material. The insulator 5 in turn supports an intermediate housing 6 which includes one of the terminals 7 of the circuit breaker, the terminal being electrically connected through a sliding contact at 8 to the movable rod contact 4. The intermediate housing 6 may, if desired, contain a current transformer 8' surrounding the rod contact 4.

Supported on the intermediate housing is an upper ceramic insulator 9 which contains the main contact structure and arc interrupting apparatus. A piston 10 which is secured to and carried by the rod contact 4 is reciprocally movable within a cylinder 11, the contact rod being tubular in construction and in communication with said cylinder below the piston 10 by means of apertures indicated at 4'. The tubular contact is open at its upper end so that when the rod is moved downward in accordance with the circuit opening operation, arc extinguishing liquid in the switch chamber, the level of which is indicated at 12, is projected from the cylinder upward through the tubular contact to the point of contact separation. The coating fixed contact at 13 is resiliently mounted at 13' and is suitably electrically connected to the other circuit breaker terminal at 14. The circuit breaker can also be provided with suitable baffle and cooling structure indicated at 12' for preventing throw of oil.

Referring more particularly to the movable contact structure, a contact element 15 is carried at the end of the tubular contact for directly engaging the fixed contact 13. The contact 15 is normally surrounded by and operable within an insulating member 16 forming a nozzle-like structure for guiding the jet of oil from the tubular contact.

As best illustrated by Fig. 2 which is an enlarged view of a generally similar contact structure, the insulating member 16 may, if desired, be formed in part at least as an intermediate contact between the coating contacts 13 and 15. Referring more particularly to the construction shown, a movable contact 15 which is suitably mounted at the upper terminal of the hollow rod contact 4 is provided with an arcing tip 17. The insulating nozzle 16 is mounted in sleeve-like fashion on the rod contact 4 and is normally

biased by a spring 18 towards the end of the contact into engagement with contact 13. The insulating nozzle 16 which is operatively connected through a pin and slot connection 19 and 20 to the rod 4 is accordingly limited to a predetermined range of movement indicated at "a".

The intermediate contact at 21 comprises the upper part of the nozzle structure and is formed as an annular member so that the arcing contact 17 extends through the same the contact 15 however closing the nozzle exhaust passage. In the closed circuit position shown, the fixed contact 13 and the intermediate contact 21 are in direct engagement and the contact 15 engages in a valve-like manner the intermediate contact. As in the previous instance the fixed contact is resiliently mounted at 13' in order to insure proper contact pressure.

In this arrangement wherein the nozzle member forms an intermediate contact the actual contact area is completely surrounded by external oil and is therefore thoroughly cooled, thereby resulting in efficient contact operation.

For the purpose of preventing excessive pressures in the cylinder 11 and for limiting application of the oil jet during the opening stroke of the breaker, ports 11' are formed in the cylinder walls a predetermined distance below the piston 10. These ports also facilitate refilling of the cylinder with oil when the breaker is closed and also reduce the power required for operating the contact rod 4. It will be apparent that the ports prevent any appreciable projection of oil through the arc before the arc has lengthened a predetermined extent. That is, it is desirable that the jet of oil be applied when the arc has reached a length most favorable for circuit interruption. The piston 10 is suitably provided with ports 23 which coact with a flap valve 23 in a well-known manner.

The operation of the device is as follows: When the contact rod is moved downward in accordance with the circuit opening operation, the piston 10 forces oil from the cylinder 11 into the tubular contact through the openings 24. The oil passes outward through the openings 25 around the contact 15 and exhausts through an annular opening formed between the contacts 21 and 15 immediately upon separation of contacts 13 and 21 as presently described. The vents 11' in the cylinder 11 provide for initial release of the oil under pressure.

It will be noted that the nozzle 16 which is biased by the spring 18 into engagement with the contact 13 remains in such engagement by reason of the lost motion connection at 19 and 20 until the contact 15 has moved through the distance "a". During this contact movement an arc of predetermined length is drawn between the contacts 15 and 21. When the lost motion between the rod contact 4 and the nozzle 16 is taken up contact separation at 13 and 21 is immediately effected with the result that a strong oil blast is directed through the aforesaid annular passage 65 into the arc and towards the fixed contact 13. That is, after the movable contact has completed that part of the stroke indicated at "a", the nozzle 16 moves as a unit with the rod contact 4 so as to separate contacts 21 and 13. The arc then tends to strike between the contact 13 and the arcing tip 17 by reason of the radial converging force of the jet exhausting through contact 21 so that it is again centrally positioned and in the zone swept by the oil jet from the 75 nozzle.

Upon closing of the circuit breaker, the oil enters the cylinder 11 by the ports 22 in the piston which are now unobstructed by the flap valve 23. The contacts engage in the reverse order, that is, the contacts 13 and 21 first engage and subsequently the tubular contact rod 4 in compressing the spring 18 so as to force the nozzle against the contact 13 forces the contact 15 into engagement with intermediate contact 21.

In Fig. 3, there is shown a generally similar arrangement wherein the nozzle 16 is composed entirely of insulating material. In the closed circuit position the movable contact 15 extends through the exhaust passage of the nozzle directly to engage the fixed contact 13. As in the previous instances the movable contact 15 carries the piston 10 and is surrounded by a tubular structure 26 which provides an annular space through which the oil is forced by the piston during the circuit opening operation.

The operation is believed to be apparent without further description, the piston 10 after predetermined movement thereof within the cylinder 11 projecting oil upwardly through the ports 27. The insulating nozzle which remains in engagement with the fixed contact 13 during the initial opening movement of the contact 15 is finally picked up by the movable contact structure and moved away from the contact 13 so that the nozzle exhaust passage is clear. The arc which is formed between the central part of the contact 13 and the arc tip of the arcing contact 15 extends generally axially of the insulating nozzle and is therefore subjected to a radial oil blast through the annular exhaust passage formed between the contact 15 and the nozzle 16. This radial oil blast serves to envelop the arc and sweep away the arc products so as effectively to extinguish the arc.

Fig. 4 illustrates a simplified form of the nozzle arrangement wherein the nozzle serves a dual purpose, namely that of creating the fluid pressure and guiding the oil blast through the arc. The interrupting or arc chamber which is formed by the insulating cylinder 28 serves as the cylinder for the piston structure carried by the movable rod contact 4. The piston in the present instance is composed of a funnel-like member 28 which is suitably secured at the desired position to the movable contact rod by means of a clamping collar 29. The upper or exhaust opening of the inverted funnel structure is defined by an insulating nozzle 30 which is positioned adjacent the fixed contact 13.

When the circuit breaker is opened the funnel 28 is moved downward by the rod 4 within the cylinder 26, the open circuit position being indicated by dotted lines. The oil beneath the funnel within the cylinder 26 is accordingly forced through the annular opening 31 formed between the contact member 15 and the insulating nozzle 30 to sweep the arc formed between the contacts 13 and 15. Accordingly a strong jet of oil is projected radially on the arc at the contact 15 throughout the entire stroke of the movable contact structure.

Figs. 5 and 6 illustrate another form of circuit breaker in the closed and partly open positions respectively. In this arrangement the fixed contact structure is modified, the movable contact 15 as in the previous instances being operable within an insulating nozzle 16. When the movable contact structure is lowered the contact 15 and nozzle 16 coact in the manner previously described and an oil blast is produced generally indi- 75

cated by the flow direction arrows 32 through the annular opening at the nozzle exhaust.

The fixed contact structure comprises an annular contact 33 which is resiliently mounted on a spring 34, and a centrally positioned contact rod 35 which is also biased towards a lower limiting position by a spring 36.

When the circuit breaker is closed as illustrated by Fig. 5, the contact 15 directly engages the contact 35 and holds it retracted against the bias of spring 36, the contact 15 also engaging an annular contact seat formed by a cylindrical member 37 constituting a part of contact 33.

When the circuit breaker is opened the contact 15 first separates at the contact seat at 37, the contact rod 35, however, remaining in following engagement. After a limited movement defined by the stop member 38, the contacts 15 and 35 separate and the arc formed between the same is subjected to the oil blast above described. The oil blast is directed at the tip of contact 35 which in its limiting position extends through an opening in an insulating plate 39. The plate 39 serves as a partition to prevent restriking of the arc between the contacts 15 and 33.

Fig. 7 shows an arrangement wherein the oil blast is directed transversely of the arc, the oil jet in this case being projected through the tubular rod 4 of the movable contact in a direction indicated by the flow arrows 40. The insulating nozzle 16 is provided with a lateral port 16' and carries an intermediate contact 41. The fixed contact is indicated at 13 and the movable contact member at 15. In the closed circuit position of the breaker, the intermediate contact 41 engages the fixed contact 13 and the contact 15 in turn engages contact 41. It is not essential that the nozzle 16 be spring biased toward the fixed contact 13 since the oil which is forced through the tubular contact 4 upon opening of the breaker lifts the intermediate contact 41 and so brings the exhaust passage of the nozzle into alignment with the fluid passage formed by the movable contact structure. Accordingly the arc between the contacts 15 and 41 is transversely swept by the oil jet. In this arrangement high pressures are automatically avoided within the nozzle 16.

In the modification shown by Fig. 8, the arc is subjected to separate oil blasts at its roots, namely, at the contacts 13 and 15. In this arrangement, the lower part of the cylinder 11 in which the piston 10 operates, communicates with a conduit 42 which terminates in a nozzle 43 positioned adjacent the fixed contact 13. The exhaust passage of the nozzle is so positioned that the fluid jet is substantially transverse of the arc at the contact 13.

When the circuit breaker is opened by the contact rod 4 as indicated by Fig. 8, the downward movement of the piston 10 produces a primary jet of oil in the manner previously described through the nozzle 16 and around the movable contact 15 and a secondary jet of oil directly from the nozzle 43 towards the fixed contact 13. Accordingly substantially throughout the opening operation the arc formed between the contacts 13 and 15 is subjected to the action of an oil jet or jets.

The conduit 42 may be replaced if desired by an annular passage formed between the cylinder 26 and an internal concentrically arranged cylinder, the aforesaid annular passage communicating with the lower part of the cylinder 11 and

terminating at its upper part in one or more nozzle passages such as indicated at 43.

In the interruption of high voltage power circuits, it may be advantageous to utilize a plurality of transverse oil jets, each jet tending to form a film of insulating fluid for interrupting the arc. It is also advantageous to direct one of these oil jets directly on the crater or root of the arc. Figs. 9 to 12 inclusive, illustrate a particular form of high voltage breaker wherein a plurality of transverse oil jets are utilized in the manner above referred to.

Fig. 9 which is an axial view of the contact arrangement and illustrates the breaker in the closed circuit position, the contact 15 carried by the rod 4 and the fixed contact 13 being in direct engagement. The rod 4 is connected to the piston 10 and forms with the insulating cylinder 26 an annular space communicating with the piston cylinder 11. The oil in accordance with the circuit opening movement is forced by the piston 10 upwardly through the cylinder 26 generally in the manner of Fig. 3. The oil exhausts through the arc by way of a plurality of double oil jets that are directed in divergent directions as presently described.

Referring more specifically to the disclosure the arc interrupting device which is carried at the upper part of the tube 26 comprises an insulating structure forming, as shown by Fig. 9, a main port 45 leading from the cylinder 26 directly to a pair of transverse passages 46 and 47 adjacent the point of contact engagement. These passages may be nozzle-shaped in form. A double jet is therefore directed transversely of the arc upon initial opening of the circuit.

A second double jet which subsequently comes into action as the circuit opening operation proceeds is indicated by Fig. 11 which illustrates a sectional view of the apparatus shown by Fig. 9, 120 degrees from the position shown in Fig. 9. This is best illustrated by Fig. 10 which is a plan view of the breaker arrangement, line B—B indicating the section shown by Fig. 11. In Fig. 11 a second double jet is in communication with the cylinder 46 through a main passage 48 which terminates in the transverse nozzle passages 49 and 50. Accordingly when the contact 13 has cleared these passages the second double blast comes into action.

A third double jet as indicated by Fig. 12, the section being indicated by line C—C of Fig. 10, is spaced 120 degrees from the jets shown by Figs. 9 and 11 and is directed through a main passage 51 which communicates with the cylinder 26 and terminates in the transverse passages 52 and 53. This arrangement provides a third transverse double blast across the arc when the contact 13 clears the passages 52 and 53.

Accordingly it will be noted that the three double transverse oil jets are not only axially spaced with respect to the opening stroke so as to cause application of the oil jets in successive stages, but each initial application of an oil jet is at the crater or root of the arc at the contact 13. The interrupting action is therefore quite effective throughout the entire opening stroke. It will be apparent, of course, that the shape of the main oil passages 45, 48 and 51, and the corresponding transverse blast passages may assume different forms so as to reduce as much as possible the fluid friction.

One of the important advantages in the radial or diverging arrangement of the jet passages resides in the fact that the reaction of the various

Jets offset each other as regards the transversal thrust exerted on the movable contact rod. In this manner, binding of the contact rod is avoided.

It shall be understood that the relative axial spacing of the transverse jets may be selected in accordance with the operating characteristics required. That is, when it is desired to interrupt a very high voltage circuit at low current, it is advantageous to increase the axial distance between the double oil jets. Such an arrangement, however, is not advantageous in the case of a very high voltage circuit at high current since there would be a comparatively high back pressure interfering with the downward stroke of the piston. It is therefore preferable to reduce the spacing between the jets and to increase the width or cross sectional area of the jets so that the arc gases generated may readily escape prior to the actual oil blast.

20 The application of the oil jet is also most effective when the contacts are sufficiently separated so that the arc interruption may be accomplished at the first passage of the voltage through zero. Too early application of the oil jet may result in high voltage surges without necessarily extinguishing the arc. The desired delay in applying the oil jet may be obtained, as previously indicated, by providing ports as at 11' in the main piston cylinder 11 through which 25 the oil may escape during the first few centimeters of the piston opening stroke.

It should be understood that my invention is not limited to specific details of construction and arrangement thereof herein illustrated, and that 30 changes and modifications may occur to one skilled in the art without departing from the spirit of my invention.

What I claim as new and desire to secure by Letters Patent of the United States is:

40 1. An electric circuit breaker of the liquid blast type comprising relatively movable contact structure, including a nozzle-like member, a contact element coacting as a unit with said member and positioned centrally thereof, said element mounted for limited movement with respect to the nozzle exhaust, and a relatively fixed coacting contact element, an arc-extinguishing liquid and piston structure operatively related to said contact structure for projecting a blast of said liquid through said nozzle and across said first-named contact element in the direction of said first coacting contact element upon opening of the circuit.

55 2. An electric circuit breaker of the liquid blast type comprising relatively movable contact structure including a nozzle-like member, a contact element operable between limits within said member and positioned centrally with respect to the longitudinal axis of said member so as to substantially close the nozzle exhaust in the closed circuit position, and a coacting contact element generally in alignment with said axis, an arc-extinguishing liquid and piston structure operatively related to said contact structure for projecting a blast of said liquid through said nozzle along said axis and in the direction of said coacting contact element upon predetermined separation of said contact structure.

70 3. An electric circuit breaker of the liquid blast type comprising relatively movable contact structure including a nozzle-like member secured to and movable with a part of said structure, said member having a lost-motion connection with respect to said part of said structure, means for biasing said nozzle-like member towards its

closed circuit position, an arc-extinguishing liquid, operating means for effecting separation of said contact structure and subsequent movement of said nozzle-like member, and piston structure operable in accordance with the circuit opening operation for projecting a blast of said liquid through said nozzle for interrupting the arc formed at said contact structure in accordance with said movement of said nozzle-like member.

4. An electric circuit breaker of the liquid blast type comprising a fixed contact, a coacting movable contact, a nozzle member having a lost-motion connection with said movable contact, the passage through said nozzle member being closed in the closed circuit position of said contacts, an arc-extinguishing liquid, operating means for effecting circuit opening of said contacts, said lost-motion connection effecting subsequent movement of said nozzle member and opening of its passage, and piston structure operable in accordance with the circuit opening movement for projecting a blast of said liquid through said nozzle for interrupting the arc formed between said contacts.

5. An electric circuit breaker of the liquid blast type comprising relatively movable contact structure including coacting contacts and a contact operable intermediate said contacts, a nozzle member connected to said intermediate contact, means providing a lost-motion connection between said nozzle member and one of said coacting contacts, the passage through said nozzle member being closed in the closed circuit position of said contact structure, and arc-extinguishing liquid, operating means for effecting initial separation of one of said coacting contacts and said intermediate contact and for effecting subsequent movement of said nozzle member to open said passage and to separate said intermediate contact and the other of said other coacting contacts, and fluid pressure means for projecting a blast of said liquid through said nozzle for interrupting the arc formed between said contacts upon opening of the circuit.

6. An electric circuit breaker of the fluid blast type comprising a fixed contact, a movable tubular contact, an intermediate contact adapted to form two arcs in series between said fixed and movable contacts, an insulating member having a sleeve-like fit with respect to said tubular contact and forming with said intermediate contact a fluid passage in alignment with the bore of said tubular contact, said insulating member having a lost-motion connection with said tubular contact, means resiliently biasing said insulating member towards said fixed contact, opening movement of said tubular contact causing initial separation of said tubular and intermediate contacts within said insulating member, said lost-motion connection causing subsequent separation of said intermediate and fixed contacts, an arc-extinguishing liquid and fluid pressure means operated in accordance with the circuit opening movement for projecting a blast of said liquid through said tubular contact and the passage formed by said insulating member and intermediate contact for interrupting the arc.

7. An electric circuit breaker of the fluid blast type comprising a pair of relatively movable contacts including a rod contact, a tubular member surrounding said rod contact and terminating in an insulating sleeve forming with said tubular member a fluid passage to the point of engagement of said contacts, said insulating member be-

ing mounted for limited movement with respect to said tubular member and normally biased so as to close said passage in the closed circuit position, an arc-extinguishing liquid and a piston movable with said contact and tubular member for projecting a blast of said liquid through said tubular member to exhaust at the point of separation of said contacts, separation of said contacts being effected prior to movement of said insulating member for opening said fluid passage.

8. An electric circuit breaker of the fluid blast type comprising relatively movable contact structure including a resiliently mounted contact, a coacting movable contact and an annular current-carrying contact normally engaged by said movable contact, an insulating member coacting with said movable contact and forming therewith a fluid passage adjacent the region of contact separation, an insulating partition having an aperture generally in alignment with said passage positioned between said current-carrying contact and insulating member, said movable contact being withdrawn into said insulating member in the circuit opening operation, said movable contact being initially separated from said current-carrying contact and subsequently separated from said resiliently biased contact adjacent the aperture in said insulating partition, an arc-extinguishing liquid, and fluid pressure means

actuated in accordance with the circuit opening operation for projecting a blast of said liquid through the passage formed by said insulating member and towards said resiliently biased contact.

9. An electric circuit breaker of the liquid blast type comprising relatively movable contacts, means forming a sleeve-like arc-interrupting structure in which said contacts coact, separation of said contacts being in a direction generally coincident with the longitudinal axis of said structure, an arc-extinguishing liquid in which said contacts are immersed, piston structure operatively connected to one of said contacts for creating liquid pressure in said structure upon opening of the circuit, and insulating means constituting a part of said structure forming a plurality of exhaust passages for said liquid, said passages being in direct communication with said piston structure and spaced axially along the path of the arc formed between said contacts so that said liquid in exhausting traverses the arc path, said passages likewise being radially positioned so as to exhaust in diverging directions, the liquid blast being deferred until the passages respectively are cleared by the contact-opening operation.

GEORGES BALACHOWSKY.

CERTIFICATE OF CORRECTION.

Patent No. 2,111,416.

March 15, 1938.

GEORGES BALACHOWSKY.

It is hereby certified that error appears in the printed specification of the above numbered patent requiring correction as follows: Page 4, first column, line 52, claim 1, for the word "first" read fixed; and that the said Letters Patent should be read with this correction therein that the same may conform to the record of the case in the Patent Office.

Signed and sealed this 3d day of May, A. D. 1938.

(Seal)

Henry Van Arsdale,
Acting Commissioner of Patents.
